FIG. 1.

FIG. 2.

FIG. 3.

FIG. 4.

Inventor:
Ernest Cyril Adolph
per A. W. Plucker
Attorney.

UNITED STATES PATENT OFFICE.

ERNEST CYRIL ADOLPH, OF GREEN LANE, AUCKLAND, NEW ZEALAND.

BEDSTEAD-JOINT.

1,318,823.

Specification of Letters Patent.

Patented Oct. 14, 1919.

Application filed December 29, 1917. Serial No. 209,573.

To all whom it may concern:

Be it known that I, ERNEST CYRIL ADOLPH, a citizen of the Dominion of New Zealand, and residing at Green Lane, Auckland, in the Provincial District of Auckland, in the Dominion of New Zealand, have invented certain new and useful Improvements in Bedstead-Joints, of which the following is a specification.

10 This invention relates to joints for securing the ends of rails to the head and foot of a bedstead, and more particularly to that class of joint wherein a coachscrew has a head projecting from the end of a rail and adapted to be engaged by a bracket or plate secured to the head or foot of the bedstead.

This invention provides improvements in the said bracket or plate.

20 According hereto the bracket affixed to the head or foot of a bedstead is made with a hole sufficiently large to admit freely the head of a coachscrew projecting from the end of a rail of the bedstead, and a slot 25 opening into the bottom of the hole is sufficiently large to admit the stem of the coachscrew. Flanges are thus formed for retaining the head. The back of the bracket is hollow to provide room for the head of the 30 coachscrew.

The bracket has a flange at the bottom projecting from its front face, whereon the end of the rail is supported, thereby relieving the coachscrew of the weight of the rail, 35 mattress, bed clothes and the person occupying the bed.

A web, extending from the face of the bracket to the edge of the flange, fits into a notch formed in the end of the rail. The 40 web and the flange prevent the rail from turning around upon the coachscrew.

The bracket is affixed to the face of the head or foot of the bedstead or is let in flush therewith, so that when the rail is in position the bracket is entirely hidden.

45 The invention may be conveniently and advantageously carried into practice as shown in the accompanying drawing, wherein:

50 Figure 1, is an elevation partly in section of the invention,

Fig. 2, is a rear elevation,

Fig. 3, a side elevation, and

Fig. 4, a front elevation of the bracket.

The bracket 1 is fixed to the head 1^a or 55 foot of a bedstead and has a hole 2 sufficiently large to admit the head 3 of a coachscrew 4 projecting from the end of a rail 5 of the bedstead. A slot 6 opening into the bottom of the hole 2 is sufficiently wide to admit 60 the stem of the coachscrew 4. Flanges 7 are thereby formed for retaining the head 3, the said flanges being sufficiently thin to allow free movement of the head in the hollow of the bracket.

65 The flange 8 projects forwardly from the bottom of the bracket, and forms a rest whereon the end of the rail 5 is supported, thereby relieving the coachscrew 4 of weight.

The web 9 extends across the angle formed 70 by the flange 8 and the bracket 1, and engages a notch 10 provided in the end of the rail 5. The web and the flange prevent the rail 5 from turning around on the coachscrew.

75 Fig. 1 shows the bracket affixed to the face of the head 1^a and Fig. 3 shows the bracket sunk in flush with the face of the said head.

What I do claim and desire to secure by Letters Patent of the United States is:— 80

The herein described joint comprising a bracket consisting of a hollow plate having a hole and a slot opening into the bottom of the hole, a coachscrew having its head projecting from the end of a rail and adapted 85 to enter the hole and its stem to enter the slot, a flange projecting from the front of the bracket whereon the end of the rail is supported, and a web extending across the angle formed by the flange and bracket to 90 engage a notch in the rail, substantially as set forth.

In testimony whereof I have signed my name to this specification in the presence of two witnesses.

95

ERNEST CYRIL ADOLPH.
